UNITED STATES PATENT OFFICE.

JULIUS DINHOFER, OF NEW YORK, N. Y.

CIGAR LIGHTER.

Application filed January 25, 1927. Serial No. 163,334.

This invention relates to a cigar or cigarette lighter and has for its object to provide such a device which will be composed of few parts; which will be thoroughly reliable in operation and which will not be likely to get out of order readily or to ignite in the pocket.

With these objects and such other objects as may hereinafter appear, in view, I have devised the particular arrangement of parts hereinafter set forth and more particularly pointed out in the claims appended hereto.

Reference is to be had to the accompanying drawing, forming a part hereof in which

Figure 1 is a longitudinal sectional view of the cigar lighter mechanism;

Figure 2 is a plan view of the same, with parts being shown in section to disclose construction;

Figure 3 is a sectional view on the line 3—3 of Figure 2, looking in the direction of the arrows;

Figure 4 is a side elevation of the upper end of the lighter, with parts being broken away to disclose construction; and

Figure 5 is an end view of the part of the lighter disclosed in Figure 4.

Throughout the various views of the drawings, similar reference characters designate similar parts.

In the embodiment of my invention disclosed in the accompanying drawing, 1 indicates the containing reservoir or body of the lighter, the same being of any desired form and being preferably of a substantially flat shape, with rounded ends. At 2 is shown a plate arranged to completely close and snugly fit within one end of the casing 1, and secured to said plate is a lattice work or cage 3. This cage 3 is so shaped that it snugly fits within the outer casing 1 and it acts to hold absorbent cotton 4 or similar material, which is usually saturated with kerosene, gasoline or some other inflammable liquid.

Secured to and extending upward from the plate 2 is a tubular support or stud 6, through which a wick 5 extends, said wick lying in the absorbent cotton 4 within the cage 3 and passing upward through the tube 6 as is clearly disclosed in Figures 1 and 4. The tube 6, in co-operation with a similarly shaped stud 7 acts to rigidly support a horizontally extending tubular body 8. This tubular member 8 extends substantially parallel to the top face of the closure plate 2

and it is provided with a cut-away part or aperture 9 which is located directly over the upper end of the tube 6 and wick 5 held therein. The purpose of this opening is to permit the light or flame from the wick 5 to extend through the tube 8 and ignite a cigar or cigarette or the like.

At 10 is a tubular slidable member, which snugly fits within the outer tube 8 and is adapted to slide back and forth therein as will be hereinafter set forth. This movable member 10 is provided in its lower face with a slot 11, so that said member 10 can freely move back and forth and while doing so, will clear the upwardly projecting wick tube 6.

Secured to the inner face of the outer tube 8 is a pair of upwardly extending ears 12, between which is rotatably mounted a striking wheel 13, which is provided with a roughened periphery as is common in wheels of this character.

At 14 is a pinion, which is fixed on the same shaft 16 that the wheel 13 is secured on and said pinion 14 meshes with a roughened surface or rack 15 provided on the inner face of the slidable tubular member 10. The member 10 is normally thrust outward by the impulse of a coil spring 17 which is contained within the outer tube 8 and abuts against the end 18 of the inner tube 10. The opposite end of said spring 17 bears against a plug 19 which is threaded into the end of the outer tube 8. Said plug 19 is provided with a rounded end 20, which corresponds in shape to a similar rounded end 21 found on the slidable tube 10. Thus, the both ends of the lighting mechanism correspond in appearance and provide no unsightly projections or parts. The plug 19 is secured to a narrow tube 22, within which a coil spring 23 is located. Said coil spring 23 normally tends to thrust out of said tube a piece of igniting material 24 and causes the end of said igniting material 24 to be constantly forced against the periphery of the wheel 13. When said section of striking material 24 becomes worn out or completely used, the plug 19 may be unthreaded from the end 18 of the outer casing or tube 8 and a new section of striking material may be fitted into the end of the narrow tube 22.

The tube 22 is preferably made of smaller diameter so that it passes within the coils of the spring 17 and does not in any way interfere with the operation of said spring.

From the foregoing, the manner in which my improved device operates will be readily understood. It will be seen that the upper face of the sliding tubular member 10 is provided with an aperture or opening 25 which is similar in size and general shape to the aperture 9 in the outer tubular casing 8. To cause the lighter to operate, it is merely necessary to place the thumb against the 10 rounded end 21 on the tube 10 and press inwardly against the tension of the spring 17. When this is done, the inward movement of the member 10 causes the rotation of the pinion 14 and a consequent rotation of the striking wheel 13. As this striking wheel 13 bears against the face of the block of striking material 14, sparks are caused to be thrown and as said sparks are confined within the tubular body 10, they readily cause 20 the wick 5 to be ignited.

It will also be seen that when the tubular member 10 is forced inside of the outer tube 8, the apertures 9 and 25 will come into registration, so that the flame can pass up 25 through these aligned apertures and be accessible. To cause the flame to be extinguished, it is merely necessary to release pressure on the end of the member 10 and the spring 17 will thrust the member 10 back 30 to its normal position disclosed in Figures 1 and 2, thereby causing the apertures 9 and 25 to be placed out of alignment so that the end of the wick 5 is covered and the flame, being cut off from an air supply, will be 35 immediately extinguished. It will be seen that the slot 11 in the bottom of the slideable tubular member 10 is provided with shoulders 26 and these shoulders act to serve as 40 abutments against the tube 6 and limit the outward sliding movement of the member 10.

From the foregoing, it will be seen that the cigar lighter disclosed is of extremely simple construction, that its parts are entirely enclosed, so that the possibility of accidental ignition is prevented, and that dust

and dirt are also prevented from reaching any of the operating parts.

Having described one embodiment of my invention, it is obvious that the same is not 51 to be restricted thereto, but is broad enough to cover all structures coming within the scope of the annexed claims.

What I claim is:

1. A device of the class described comprising a fuel reservoir, a pair of supporting struts extending therefrom, a pair of telescoping tubular members supported by said struts, one of said struts constituting a hollow passage for a wick which extends therethrough and into one of the telescoping members, a rotary striking wheel adapted to be rotated by telescopic operation of the tubular members, a section of igniting material held against the striking wheel, a support for said igniting material and a spring surrounding said support and normally tending to separate the telescoped members.

2. A device of the class described comprising a fuel reservoir, a pair of tubular telescoping members separated from the reservoir and wholly containing a lighting device, said members being connected to the body of the fuel reservoir by several struts, one of said struts being tubular and a wick passing through said strut and extending from the lighting device to the reservoir.

3. A device of the class described comprising a fuel reservoir, a lighting device separate therefrom and contained in a pair of telescoped tubular members, means rotated by telescoping movement of said members for causing operation of the lighting device, and a pair of struts connecting the lighting device and fuel reservoir, one of said struts being tubular and constituting a wick passage from the reservoir to the lighting device.

Signed at the city, county and State of New York, this 22nd day of January, 1927.

JULIUS DINHOFER.
